UNITED STATES PATENT OFFICE.

GEORGE C. L. TISCH, OF ELIZABETH, NEW JERSEY, ASSIGNOR TO TISCH KNITTING MACHINE CO., OF ELIZABETH, NEW JERSEY, A CORPORATION OF NEW JERSEY.

TAKE-UP FOR KNITTING MACHINES.

Application filed February 20, 1924. Serial No. 694,155.

To all whom it may concern:

Be it known that I, GEORGE C. L. TISCH, a citizen of the United States, and a resident of Elizabeth, in the county of Union 5 and State of New Jersey, have invented a new and Improved Take-Up for Knitting Machines, of which the following is a full, clear, and exact description.

This invention relates to knitting machines and particularly to an improved take-up for knitting machines of the Tisch type and has for an object the provision of an improved gripping and lever mechanism wherein the speed of take-up may be varied 15 without changing the usual driving cam.

Another object of the invention is to provide an improved grip for the take-up mechanism of a knitting machine wherein the take-up mechanism may be operated 20 very slowly or at a comparatively high speed and substantially any desired distance within certain limits upon each operation.

In the accompanying drawings—

Figure 1 is an end view of a Tisch knitting machine with an embodiment of the 25 invention applied thereto.

Figure 2 is an enlarged elevation of a gripping structure and associated parts disclosing certain features of the invention.

Figure 3 is a top plan view of the structure shown in Figure 2.

Figure 4 is a fragmentary sectional view through Figure 2, approximately on line 4-4.

Figure 5 is a side elevation of the gripping band shown in Figure 2.

Figure 6 is a fragmentary view showing one end of the band actuating lever illustrated in Figure 2.

Referring to the accompanying drawings by numerals, 1 indicates the frame of the knitting machine which is of a well known type and, therefore, will not be described in detail (see Patent No. 457,265). The knitting 40 machine is provided with a shaft 2 driven by suitable power and carries a bevel gear 3 which meshes with and rotates the bevel gear 4. Connected with the bevel gear 4 is a cam 5 adapted to engage the lever 6

45 for raising the same, said lever being pivotally mounted at 7 on part of frame 1. The lever 6 is provided with a comparatively long slot 8 through which a connecting bolt 9 extends, said connecting bolt being of any 50 desired structure and acting to pivotally

connect one end of the link 10 of lever 6, the opposite end being pivotally connected by a connecting bolt 11 to the strap lever 12. The bolt 11 extends through the slot 13 and is adjustable along the slot in a similar manner to the way the bolt 9 is adjusted along the slot 8, whereby the throw of the lever 12 may be varied by adjusting either of these bolts or both of the same without interfering with the cam 5. 60

The bolts 9 and 11 act as connecting members and also as pivotal members but do not rigidly secure the parts together. 65

For instance, if a greater throw of lever 12 is desired, bolt 9 may be moved outwardly 70 on lever 6 or bolt 11 may be moved inwardly on lever 12. The lever 12 is provided with a pair of apertures 14 and 15 (Figure 6), said apertures registering with the apertures 16 and 17 on the gripping strap 18 when the parts are assembled as shown in Figures 2 and 3. Suitable pins 19 and 20 are fitted into these apertures, said pins permitting the lever 12 to move on these pins whereby the section 21 may move upwardly as shown in 75 Figure 5 while the section 22 is moved downwardly. This action takes place whenever the lever 12 is swung upwardly by the link 10. The sections 20 and 21 merge into a substantially annular clamping band 23 80 which may be of any desired thickness and which normally frictionally engages the surface of the sleeve or drum 24 which is secured to the shaft 25 in any suitable manner, as for instance, by the set screw 26. 85 The shaft 25 is connected with a suitable drum or other mechanism on which the knit goods is wound, whereby it may be moved in proper time to the operation of the other parts of the machine. The head of shaft 25 is journaled in the upper end of a suitable bracket 27 which is mounted in any desired manner on part of the frame 1. 90

In operation, the gripping band 23 is positioned as shown in Figures 1 and 2 100 and the other parts are arranged substantially as shown in Figure 1. As the cam 5 rotates, the lever 12 will be moved upwardly and then downwardly again under the action of gravity upon each rotation of the cam 5. 105 As the cam moves in one direction, the lever 12 is moved upwardly and the first action is to cause the band 23 to tightly grip the drum 24 and then to partly rotate this drum. 110 As the band 23 is more or less frictionally

engaging the entire surface of drum 24, the gripping action thereof will be quick and positive so that usually the lever 12 moves but a short distance before gripping 5 takes place and the remaining part of the movement is used in rotating partly shaft 25 and associated parts. By providing this form of grip, the shaft 25 may be partially rotated a very short distance upon each 10 movement of lever 12 or the parts may be set to cause a comparatively large partial rotation.

Heretofore, ratchet wheels for driving pawls have been used and the limitation to 15 the take-up action was the size of the teeth. The ratchet wheel might be moved forward more than one tooth but could not be moved forwardly less than one tooth and, consequently, in knitting certain kinds of goods, 20 the take-up was not proper and new ratchet wheels were required having smaller or greater diameter. This adjustment and the substitution of new cams 5 for varying the throw of the actuating lever was more or less objectionable. In the present invention, 25 the structure may be quickly and easily adjusted to give any desired take-up action without substituting any part. In order to more readily adjust the respective levers 6 and 12, suitable legends, as for instance, 30 numbers 28, may be used on lever 12 and other numbers 29 on lever 6, said numbers referring to the graduations on these levers.

What I claim is:

35 1. In a take-up for knitting machines, a gripping structure, said gripping structure comprising a resilient gripping band divided at one point only, a pair of radially extending members projecting from the band 40 adjacent the point where it is divided, each of said members having an aperture in the outer end, one of said radially extending

members having a right-angle offset section, an actuating lever extending axially from said members, and a pair of pivotal pins 45 extending laterally from said lever, said pins fitting into the respective apertures in said radially extending members.

2. A take-up for knitting machines, a rotatable drum, an actuating gripping band 50 surrounding said drum, a lever formed with a longitudinally arranged slot operatively connected with said band in such a manner that when the lever is swung in one direction it will cause the band to grip said drum and partially rotate the drum, a link, means for pivotally connecting one end of said link to said lever at different points along said slot, a power lever having a longitudinally arranged slot, means for pivotally connecting 60 the opposite end of said link to said power lever at any place along said slot, and a cam for moving said power lever.

3. In a take-up for knitting machines, a drum, an actuating gripping band surrounding said drum, said band being integral throughout and divided at one point, said band at the point of dividing having radially extending arms normally spaced apart, one of said arms at the outer end 65 overlapping the other, each of said arms having an aperture, said apertures being arranged radially in alignment, and a lever extending radially from said arms, said lever overlapping said arms, and a pair of pins connected with said lever and extending loosely through said apertures whereby when said lever is moved in one direction said arms will be brought toward each other for causing said band to grip said drum and partially rotate the drum and when moved in the opposite direction to positively 70 open said band to release said drum.

GEORGE C. L. TISCH.
